UNITED STATES PATENT OFFICE.

HECTOR VON BAYER, OF WASHINGTON, DISTRICT OF COLUMBIA.

REACTING TRUSS.

SPECIFICATION forming part of Letters Patent No. 245,034, dated August 2, 1881.

Application filed December 22, 1880. (No model.)

To all whom it may concern:

Be it known that I, HECTOR VON BAYER, a citizen of the United States, residing at Washington, in the District of Columbia, have invented a new System of Trusses for Bridges, which I call "Reacting Trusses," of which the following is a description.

An ordinary truss-bridge acts upon the supports (the abutments) in a vertical direction, or, in other words, the resulting force upon the abutment is solely the weight of the truss with its load. Arch and suspension bridges act upon the abutments in an oblique direction, the resulting force upon the abutments being the weight of the bridge with its load, combined with lateral strains proceeding from the nature of construction.

The reacting truss is constructed upon the principles of an ordinary truss-bridge with this variation: that one chord and the struts are dispensed with, and that the strains which otherwise are borne by a second chord and struts are here transposed by means of pillars into the reaction upon the abutments.

I am aware of the construction of truss-bridges with only one chord, but those have a system of struts beside the ties.

The object of my invention is to economize material and labor in the construction of bridges, retaining the necessary strength and safety required.

Figure 1 is the vertical view of a reacting truss; Fig. 2, the corresponding horizontal view; Fig. 3, the end view of the same. Fig. 4 exhibits the principle and direction of forces existing in the reacting truss. Fig. 5 is a detail showing the suspension of the cross-beams from the ties.

The principal parts in the construction of the reacting truss are the pillars P, the ties (braces) t, and the chord L.

The chord is joined to the pillars some height above their support on the butments by means

of trunnions, and keeps the pillars at a fixed distance apart.

The weight W upon the truss, Fig. 4, is borne solely by the ties, so that in no case does the said weight come upon the chord. (See Fig. 5.) Said weight causes in the ties a tensile strain, a, (a.) This strain a (a) acts upon the pillar to which the ties are secured as a twofold strain, compressive, c, (c,) and bending, b, (b.) The compressive strain c (c) acts longitudinally upon the pillar, and through it upon the abutment A, (A.) The bending strain b (b) again is divided on account of the fulcrum F, forming at the point where the chord and pillar join into a compressive strain, e, (e,) upon the chord, and a lateral strain, l, (l,) at the lower end of the pillar into the abutment. The lateral strain l (l) and the compressive strain e, (e,) both acting at the same point of the pillar, will, joined together, result in the force R (R) upon the abutment.

From the foregoing it is evident, with a sufficiently strong ordinary abutment and with all parts of the construction computed as to their proper strength, that the reacting truss may take the place of any other bridge-construction, attaining the same safety as the others at a less expenditure of material and labor.

Having fully described my invention, what I desire to claim and secure by Letters Patent is—

A bridge composed of pillars, ties suspended therefrom, and a compression-chord arranged between the pillars and connected thereto above their lower ends, whereby the resulting strains are converted into a thrust upon the abutments, substantially as set forth.

HECTOR VON BAYER.
